RUDDER STEERING SLED

Le Roy O. Gierke, Edgerton, Wis., assignor of one-half per cent to William A. Solien, Edgerton, Wis.

Application September 19, 1949, Serial No. 116,572

2 Claims. (Cl. 280—21)

1

This invention relates to novel and useful improvements in attachments for sleds.

An object of this invention is to steer a sled by means of a rudder which is pivotally carried at the rear end of a sled base, the rudder being operable in response to movements of a pivoted steering handle member disposed at the front of the base.

Another object of this invention is to resiliently oppose the operation of the steering member by means of a pair of springs which react on the base and on a steering member, the steering member being fixed for movement with the handle bar member, the resilient opposition members being so arranged as to cause the rudder to return to a position which is parallel to the longitudinal axis of the base.

Ancillary objects and features of novelty will become apparent in following the description of the illustrated form of the invention.

In the drawing:

Figure 1 is an elevational view of the device; Figure 2 is a bottom view of the device shown in Figure 1;

Figure 3 is a transverse view taken substantially in the line 3—3 of Figure 2 and in the direction of the arrows;

Figure 4 is a sectional view taken substantially on the line 4—4 of Figure 2 and in the direction of the arrows, and;

Figure 5 is a sectional view taken substantially on the line 5—5 of Figure 2 and in the direction of the arrows.

The present invention relates to attachments for sleds. It is one of the purposes of the invention to steer a sled by means of manual control of a rudder operating member disposed at the front of the sled whereby movement thereof is reflected in turning movement of the rudder.

A substantially conventional sled generally indicated at 10 is disclosed as including a base 12 with a strengthening member 14 along the longitudinal edges and along the front edge thereof. A pair of side rails or runners 16 and 18 respectively are secured to hangers which depend from the base. A center rail 20 depends from the brackets 22 and 24 which are disposed on the transverse braces 26 and 28.

A plate 30 is secured to the rear end of the base and on the undersurface thereof by means of bolts 32 or other suitable fastening means such as rivets or the like. This plate has an opening 34 therein for passage of the bolt 36 which forms a part of the pivot for the rudder. A nut 38 is disposed on the bolt and seated in the housing

40 which is fixed to the mounting plate 30. The housing is juxtaposed with respect to the opening 34 and has a sleeve 42 rotatively disposed therein. This sleeve is concentric with the bolt 36 and also forms a part of the pivot, the head end of the bolt being fixed to the interior of the sleeve.

A rudder 44 which has an upturned front portion 46 is fixed to the bottom of the sleeve, as by welding. A support brace 48 extends from the curved portion 46 and is fixed to the sleeve 42. A control arm 50 is fixed to the sleeve and has a plate 52 secured thereunder as by the screws 54. In operation upon rotation of the arm 50, the support plate 52, sleeve 42 and rudder 44 rotate about the longitudinal axis of the bolt 36 as an axis of rotation.

Links 56 and 58 are secured at the ends of the control arm 50 for pivotal movement and pass through the guides 59 and 60 which depend from the brace 26.

The front ends of the links 56 and 58 are secured pivotally through the steering or control rod 64 which is fixed to the pivot pin 66. This pivot pin passes through the base 12 and also through the bearing 68 which is spaced from the rod or bar 64 by washers 70 and 72.

Another spacer 74 is disposed on the base 12 and a handle bar or steering member 76 is seated thereon. A recess 78 shaped to conform with the head 80 of the pivot bolt 66 is formed in the handle bar 76 accommodating said head.

Hangers 82 and 84 are fixed to the brace 28 and have the links 56 and 58 passed therethrough, serving the purpose of guides. The apertures in the hangers 82 and 84 are sufficiently large to allow slight lateral displacement of the links when they are operated for rudder control.

A pair of springs 90 and 92 respectively have their ends secured in the eyes 93, 94 and 95, 96. The eyes 93 and 94 are secured respectively to the hanger 82 and the control or steering bar 64. The eye members 95 and 96 are secured respectively to the hanger 84 and the control member 64. Accordingly, the springs constantly resiliently oppose the operation of the handle bar 76 and are so arranged as to cause the rudder 44 to maintain a position substantially parallel to the longitudinal axis of the base 12.

Having described the invention, what is claimed as new is:

1. In a sled which includes a base, a steering rudder disposed at the rear of said base and parallel to the longitudinal axis of the base, means pivoting said rudder to said base and a

control arm fixed to said rudder, links secured to said control arm, and means disposed adjacent the front of said base for operating said links to actuate said rudder, said operating including a handle bar with means pivoting said handle bar to said base, a steering rod secured to said base, last mentioned means for movement therewith, said links being secured to said steering rod, a transverse brace for said base located below the bottom surface of said base, hangers secured to said brace and having guide apertures through which said links pass, springs secured to said steering rod to oppose rotative movement of said steering rod, and means fastening said springs to said hangers.

2. In a sled which includes a base, a steering rudder disposed at the rear of said base and parallel to the longitudinal axis of the base, vertically arranged means pivoting said rudder to said base and a control arm fixed to said rudder, links secured to said control arm, and means disposed adjacent the front of said base for operating said links to actuate said rudder, said operating means including a handle bar with vertically arranged means pivoting said handle bar to said base, a steering rod secured to said last

mentioned means for movement therewith and said links being secured to said steering rod, and resilient means arranged parallel to said axis reacting on said base and secured to said steering rod maintaining said control rod in position so as to cause said rudder to remain parallel to said axis.

LE ROY O. GHERKE.
